UNITED STATES PATENT OFFICE.

ROBERT W. SCOTT, OF BOSTON, MASSACHUSETTS, ASSIGNOR TO SCOTT & WILLIAMS,
INCORPORATED, OF CAMDEN, NEW JERSEY, A CORPORATION OF NEW JERSEY.

KNITTING FABRICS HAVING RIBBED SECTIONS.

1,097,734.

Specification of Letters Patent.

Patented May 26, 1914.

Application filed November 26, 1913. Serial No. 803,327.

To all whom it may concern:

Be it known that I, ROBERT W. SCOTT, a citizen of the United States, and resident of Boston, in the county of Suffolk and State of Massachusetts, have invented certain new and useful Improvements in Knitting Fabrics Having Ribbed Sections, of which the following is a specification.

An object of my invention is to improve the mode of knitting a fabric or article containing a portion of ribbed web, and especially to facilitate that part of the operation which includes the doubling of the stitches of a ribbed portion of the web upon the needles of a machine to permit another web to be subsequently knitted in continuation of said ribbed web.

Another object of my invention is to improve the mode of forming fabrics partly ribbed and partly plain as for instance a stocking having a ribbed leg web and a plain foot web knit in continuation thereof.

These objects I attain in the manner hereinafter set forth, reference being had to the accompanying drawing, in which—

Figure 1 is a view of a strip of rib knitted web made according to my method as it is delivered by the knitting machine; Fig. 2 is an exaggerated view of a piece of ribbed web knitted in accordance with my invention; Fig. 3 is a similar view of another form of web knit during the practice of my invention, and Figs. 4, 5, 6, and 7 are diagrams illustrating the relative positions of the cylinder and dial needles in forming certain successive courses of the ribbed web.

The prior art operation of forming articles of the class to which my method is particularly applicable has included the formation of a section of ribbed web, the subsequent application of said ribbed web to a second machine capable of knitting the remainder of the garment, and in the particular class of manufacture concerned it has necessitated as an incident of this operation the doubling of certain loops of the ribbed web upon the same needle of the second machine. This operation has usually been performed by transferring the loops of a transfer course of a ribbed portion doubled, or in pairs, to the same implement of a transfer device.

The operation of "doubling" has included first applying to the needles the stitches of one face of the ribbed web, say those produced by the cylinder needles, and then the

stitches of the other face of the web, say those produced by the dial needles, some or all of the needles of the machine receiving two stitches. This doubling by hand of the stitches in transferring materially increases the cost of the running-on operation, and my object has therefore been to improve this step in the operation.

My improvements include the production of a ribbed knitted web whose stitches can be transferred to the needles of another or plain web machine with the same facility as in making an ordinary single transfer. This object I attain by shogging stitches in wales of one face of the ribbed web so as to cause them to cross stitches in adjoining wales of the other face of the web, and retaining them in such new relation, whereby stitches of both faces of the ribbed web can be simultaneously transferred to one and the same needle of the secondary knitting machine with the same facility as a single stitch.

In Fig. 2 of the drawing, C', C², etc. represent the needle wales of one face of the ribbed web and D', D², etc. the needle wales of the other face of the same, the stitches in wales C', C², etc. of course 3 being shogged laterally to cross the stitches in wales D', D², etc., respectively, during the taking of yarn for a course 4, and the stitches of said needle wales C', C² etc. being, in course 4, shogged back into their normal position, the stitches in said courses 3 and 4 being elongated or slackened in all of the wales, the stitches in course 3 in order to facilitate the transfer operation, and the stitches in course 4 in order to provide a more pronounced line of demarcation between the closely knitted portions of the web, although the elongation of the stitches in wales D' and D² etc. or in the wales C', C², etc. and D', D², etc. in course 4 may be omitted, if desired. The slackened stitches are of aid to the shogging movement of the instruments.

In Fig. 4 of the drawings the letters c', c², etc. and d', d², etc. represent the respective needles of the two members of the rib knitting machine, say the cylinder and dial, in respect to one another during the knitting of ordinary ribbed web, the needle c' being to the left of the needle d' and the needle c² to the right of the needle d², and so on.

After or during the formation of the slack course 3, however, as shown in Fig. 2, the needles of either needle carrier are

- shogged to right or left to the extent of one gage, as shown the dial having moved to the right, the needles c^2 , c^3 , etc. now occupying positions respectively to the left of the 5 needles d' , d^2 , etc. The slack stitches of course 4 are then drawn with the needles in this relation, as indicated in Fig. 6, which shows the dial needles at the beginning of their retracting movement, which 10 may of course occur at each needle in succession, after or during which movement the needles are shogged back to their normal relation, as shown in Fig. 7 and knitting of ordinary ribbed web is resumed.
- 15 The stresses on the yarns in courses 3 and 4 as will be obvious from Fig. 2 are such as to hold open the shogged loops of course 3 so as to provide an area y at the crossing of face and back wales, presenting an easily 20 visible opening for the needle or transfer quill, which may be thrust through both needle wale loops without requiring close vision or so much skill or exercise of care by the operator as is necessary for doubling 25 a face and a back loop of the usual construction.
- Instead of the reverse shogging operation just described, a single shogging may be employed, the result being the crossing of 30 stitches of the wales D' , D^2 , etc. by stitches of the wales C' , C^2 , etc. as shown in course 3 of Fig. 3. In this case the new relation of the face wales to the back wales, caused by the shogging of course 3, will be maintained 35 throughout the next section of ribbed web to be knit. The course 3 may be made loose or elongated, as by causing the needles to take a longer draft, to such a degree as is found desirable.
- 40 In the operation of the knitting machine for the production of stocking legs the ribbed web may first be started with a welt m or other desired finish for the top of the leg, as shown in Fig. 1, and after the 45 desired length of ribbed web for the leg has been knitted, the slackened and shogged course of stitches 3 will be produced and then a short length of ribbed web t , for raveling back to the transfer course, as usual 50 after the slack stitches of said transfer course has been applied to the needles of the footing machine, the cycle of operations being then repeated. The web thus knitted will be severed on the lines $x-x$, so as to 55 produce a number of leg blanks of ribbed web, each having the desired finish m at one end and a course or courses of slackened and shogged stitches 3, near the other end.
- 60 In the use of the improved blank, the procedure will include knitting a string work as described, severing it into a number of sections each of which may have 65 welts m , and each having shogged transfer courses 3, with short lengths t of ravel

courses to be removed at a later time; then impaling the stitches shogged into overlying relation together directly upon the needles of a second machine, or upon the points of a transfer instrument preparatory to 70 placing said loops upon the needles of the second machine. The ravel-courses having been removed, the loops so impaled will be knit through when forming the initial loops of the remaining portion of the garment 75 for instance the heel, foot and toe of a stocking. It will be observed that for my improved process I employ only familiar machines, comprising a ribber capable of making shogged work, and a footing or other 80 machine capable of knitting the plain fabric parts of the garment.

It will be understood that my improved method of making garments containing a ribbed section is particularly useful in the 85 case of tubular articles, knit by a circular operation of the instruments, since the method necessitates no complexities in the machinery required, and may be practised with the aid of the simple prior art devices 90 for shogging one needle carrier with respect to the other.

By the practice of my method, I am enabled to avoid the transfer of loops from the needles of one carrier to the other, as 95 well as avoiding the skilful and tedious hand operation of doubling the loops on the transfer quills as commonly practised in connection with ordinary rib tops.

What I claim is:

1. The method of knitting an article having ribbed parts and plain parts comprising first knitting ribbed fabric having at intervals a course of loops of one face each crossing a loop of the other face, then removing from said fabric a portion containing a course of the said crossing loops, and impaling each pair of crossed loops of said portion on the needles of a knitting machine and then knitting the remainder of 105 the fabric on said needles.

2. The method of knitting an article having ribbed parts and plain parts comprising first knitting ribbed fabric having at intervals a course of elongated loops of one face 115 each crossing a loop of the other face, then removing from said fabric a portion containing a course of the said elongated loops, and impaling each pair of elongated loops of said portion on the needles of a knitting 120 machine and then knitting the remainder of the fabric on said needles.

3. The method of knitting an article having ribbed parts and plain parts comprising first knitting continuous ribbed fabric having throughout at like intervals a series of loops of one face shogged across loops in the same course of the other face, then removing from said fabric a portion containing one 125 series of the said shogged loops and impaling 130

ing each pair of shogged loops of said portion on the needles of a knitting machine and then knitting the remainder of the fabric on said needles.

5. 4. The method of knitting an article having ribbed parts and plain parts comprising first knitting a section of ribbed fabric, shogging loops of one face thereof into crossing relation with respect to loops of the other face, then knitting another section of ribbed fabric and thereafter severing from the length of ribbed fabric a portion containing the shogged loops; thereafter impaling each crossing pair of loops on the needles 10 of a second machine, and then knitting the remainder of the fabric on said needles.

5. The method of knitting an article having ribbed parts and plain parts comprising first knitting a section of ribbed fabric, 20 shogging the loops of one face thereof into crossing relation with respect to the loops of the other face, then knitting another section of ribbed fabric and thereafter severing from the length of ribbed fabric a portion containing the shogged loops; then impaling each crossing pair of loops on the same point or quill of a transfer implement, thereafter transferring the said portion to the needles of a secend machine, and then 30 knitting the remainder of the fabric on said needles.

6. The method of knitting an article having ribbed parts and plain parts comprising first knitting ribbed fabric having at 35 intervals a course of loops of one face shogged across the loops of the same course in the other face, then separating from said fabric a portion containing one course of the shogged loops, then impaling the shogged 40 loops of said portion where they cross in pairs upon the same point or quill of a transfer implement, then raveling so much of the ribbed fabric as extends beyond the impaled courses on one side, and then transferring 45 the impaled course to the needles of a knitting machine to knit the remainder of the fabric.

7. The method of knitting an article having ribbed parts and plain parts which comprises the formation of a succession of united 50 webs wholly of rib knitting of a uniform number of wales each web having therein stitches of one face shogged across stitches of the other face in at least one course, in 55 thereafter severing said web at points near each shogged course; and thereafter apply-

ing the shogged stitches together in pairs to a transfer implement for transfer to the needles of a knitting machine capable of knitting plain fabric.

8. The method of knitting an article having ribbed parts and plain parts, which comprises the formation of a succession of united webs of rib knitting each having therein one or more loose courses of stitches shogged 60 into overlying relation in pairs, thereafter separating said webs at points near the shogged courses; and thereafter applying each pair of overlying stitches of a shogged course to a needle of a knitting machine capable of knitting plain fabric, and then knitting a continuing plain web upon said machine.

9. The method of knitting an article having ribbed parts and plain parts, which comprises the formation of a succession of united webs of a uniform number of wales of rib knitting throughout having in each web one or more courses including stitches of one face and stitches of the other face 80 shogged into overlying relation in pairs, thereafter severing said web into sections ending near a shogged course, and thereafter applying the overlying stitches of a shogged course of a section to the needles of a knitting machine capable of knitting plain fabric, and then knitting a continuing plain web upon said machine.

10. The method of knitting comprising first forming a length of tubular ribbed web 90 having in integral succession sufficient sections of fabric for a top or border for a garment, joined together by a loose course for transfer to the needles of another machine in doubled relation, the operation including 95 shogging the face wales of one section of fabric into a different relation with respect to the back wales at the loose course and maintaining the wales in their new relation throughout the next section of fabric, thereafter separating the fabric into portions each containing a loose course and some of the fabric of each ribbed section, and thereafter transferring the loose course to the needles of a knitting machine.

In testimony whereof, I have signed my name to this specification in the presence of two subscribing witnesses.
